UNITED STATES PATENT OFFICE.

FRANCIS A. JOHNSON, OF KANSAS CITY, MISSOURI.

AUTOMATIC REGULATOR FOR GASOLENE-BURNERS.

1,078,441.

Specification of Letters Patent.

Patented Nov. 11, 1913.

Application filed December 17, 1912. Serial No. 737,323.

To all whom it may concern:

Be it known that I, FRANCIS A. JOHNSON, a citizen of the United States, residing at Kansas City, in the county of Jackson and 5 State of Missouri, have invented new and useful Improvements in Automatic Regulators for Gasolene-Burners, of which the following is a specification.

This invention relates to automatic regulators for gasolene burners, the object in view being to provide a regulator of the class described which is particularly designed for heating or blow torches.

The invention is particularly designed for 15 welding steel rails, the frames of locomotives, and for heating the tires of locomotives in order to facilitate putting them on and removing the same from the wheel.

A further object of the invention is to 20 provide a device of the class described which will embody a maximum degree of safety, and in which the pressure will be automatically maintained at a predetermined point, so that the air and gasolene will be properly proportioned and thoroughly mixed, 25 preparatory to ignition.

With the above and other objects in view, the invention consists in the construction, combination and arrangement of parts, as 30 will be hereinafter more fully described, illustrated in the accompanying drawings, and pointed out in the claims hereunto appended.

In the drawings: Figure 1 is a side elevation of the regulator embodying the present invention. Fig. 2 is a longitudinal section through the same. Fig. 3 is a section on the line 3—3 of Fig. 2. Fig. 4 is a longitudinal section through the pressure regulator. 40

The regulating device contemplated in this invention comprises a hollow body 1, and a neck 2 forming a part of the body, and extending substantially at right angles to the main part of the body, as shown in Figs. 1 and 2. At one end, the body is internally threaded, as at 3, to enable a pipe from an air compressor to be screwed into the body, while at the opposite end the body is internally threaded, as at 4, to receive a gas pipe or hose 4', by means of which the gasolene vapor may be carried any suitable distance to the point of ignition.

The air is received in an air inlet chamber 5, and the passage of air through the body is controlled by an air valve 6 operating in

conjunction with a valve seat 7, the valve embodying a stem 8 which extends outward through a stuffing box, preferably at the top of the body, where it is provided with a hand wheel 9, by means of which the valve 6 may be adjusted into the desired proximity to its seat to regulate the amount of air passing directly through the body. Beyond the valve chamber in which the air valve 6 is mounted, the body is provided with an inwardly extending partition or flange 10 which is internally threaded, as shown, to receive an air nozzle 11 which extends centrally and longitudinally of the body, and leaves a surrounding gasolene chamber 12, from which the gasolene is taken up by the blast of air passing through the nozzle 11, and atomized as it enters the service pipe or hose.

The neck 2 comprises a gasolene passage 13 which opens out at the lower end of said neck, the latter being tapered and threaded, as shown at 14, to enable the device as a whole to be screwed into a gasolene pressure tank 15.

16 designates a gasolene feed pipe provided at its lower end with a strainer cage 17 which is situated near the bottom of the tank 15, and held in place by the tube 16. 85 This tube is threaded at its upper end, as shown at 18, in Fig. 2, while a ball check valve 19 rests against the upper extremity of the tube 16, where a seat 20 is formed for said ball check valve. This check valve is 90 employed to prevent back firing into the gasolene tank 15. Above the tube 16 and check valve 19, the gasolene passage 13 is deflected laterally to one side, as shown in Fig. 3 by the numeral 21, and the wall 22 95 separating the space 21 from the gasolene chamber 12 is provided with a conical opening forming a valve seat 23, in conjunction with which a gasolene needle valve 24 operates for regulating the flow of gasolene into 100 the chamber 12. The needle valve is provided with a stem 25 extending outwardly through a stuffing box, and provided with an operating wheel 26 at its outer end. The air and gasolene valves above described enable the quantity of air and gasolene to be 105 properly proportioned and regulated.

27 designates an air duct leading from the air inlet chamber 5 through the lower portion of the body 1, and downward through the gasolene neck 2 and outward through the lower end of said neck, as shown in Fig. 110.

2. An air tube 28 is screwed into the receiving end of the air duct 27, and has its upper open end received in a hood-shaped cap 29 which is screwed into a threaded opening in the upper part of the body, as shown at 30. A portion of the air in the chamber 5 passes upward into the cap 29 and downward through the tube 28 into the air duct 20 and continues on until it enters the 10 tank 15, thereby supplying the necessary pressure behind the gasoline to force the latter through the strainer 17 and upward past the check valve 19 into the chamber 12, from which it is drawn by the blast of air passing through the nozzle 11, the gasoline needle valve 24 regulating the amount of gasoline passing into the chamber 12. Should any water find its way into the air inlet chamber 5, such water cannot get into 15 the air duct 27, as it is trapped by the upwardly extending air tube 28.

31 designates a plug inserted in a threaded opening in the top of the body 1.

Communicating with the air duct 27, at 25 a point intermediate the ends thereof, is an air pressure regulator, comprising a body or valve casing 32, the inner end of which is threaded, as shown at 33, and screwed into an internally threaded opening 34 in the 30 neck 2. In its inner end, the body 32 is recessed, as at 35, to receive a valve holder or bushing 36, in which is arranged a sliding cone-shaped valve 37 pressed toward its seat by means of a coiled spring 38 surrounding the stem 39 of the valve. The body 32 is also chambered out to form a cavity 40, in which is placed a valve seat 41, against which the valve 37 is adapted to seat. The outer side of said valve seat is 35 recessed to form an air pressure chamber 42 which is closed by means of a diaphragm 43 held between the valve seat 41 and an internal annular shoulder 44 in said body. The body 32 is also bored out, as shown at 40 45, to receive a threaded turn plug 46 having a central bore 47, in which is received the stem 48 of a plunger head 49 which is pressed toward the diaphragm 43 by means of a coiled spring 50 encircling the stem 48 50 and interposed between the head 49 and the inner end of the turn plug 47.

Rigidly connected to the outer end of the turn plug is a milled head 52 which is of sufficient internal diameter to embrace and 55 revolve around the outer end of the body 32, the said head 52, together with the body 32, being graduated, as shown at 53 and 54, respectively, the graduations 54 being intended to represent the air pressure in pounds, 60 so that by turning the head 52, any desired pressure in pounds may be obtained in the air regulating chamber 42. By turning the head 52, the turn plug is revolved and pushes inward on the spring 50 which accordingly exerts a greater or less pressure

against the plunger head 49, and in turn against the diaphragm, tending to open the port through the valve seat 41. On the other hand, the spring 38 behind the valve 37 opposes the action of the spring 50. Air 70 enters the chamber 42 through an air inlet port 55 and emerges therefrom through a port 56 which leads back into the main air duct 27.

From the foregoing description, it will 75 now be seen that the air passing downward through the duct 27 passes by the valve 37 and through the chamber 42 and port 56 into the end portion of the duct 27, and thence into the gasoline tank. Should the 80 air pressure in the tank diminish to any considerable extent, the pressure in the chamber 42 will be correspondingly reduced, thereby allowing the spring 50 to move the plunger head and thereby force the diaphragm 43 against the end of the valve 37, unseating said valve and allowing the full air pressure to enter the chamber 42. As 85 soon as the pressure is restored, the valve 37 closes and shuts off any further increase 90 in pressure. In this way, a certain predetermined pressure is always maintained in the gasoline tank, which will insure the proper flow of gasoline under pressure to the needle valve 24.

95 What is claimed is:

1. An automatic regulator for gasoline burners, comprising a hollow body having an air inlet chamber, and an air passage leading from the chamber, an interiorly positioned air nozzle spaced from the wall of the body to form a gasoline chamber, said nozzle communicating with said air passage; an adjustable air valve controlling said passage between the air inlet chamber 100 and nozzle, a neck provided with a gasoline supply passage leading to said gasoline chamber, an air duct leading from the air inlet chamber through said neck, a self-regulating air pressure valve interposed in said 105 air duct, and an air inlet tube protecting the receiving end of the air duct.

2. An automatic regulator for gasoline burners, comprising a hollow body having an air inlet chamber, and an air passage 110 leading from the chamber, an interiorly positioned air nozzle spaced from the wall of the body to form a gasoline chamber, said nozzle communicating with said air passage; an adjustable air valve controlling 115 said passage between the air inlet chamber and nozzle, a neck provided with a gasoline supply passage leading to said gasoline chamber, an air duct leading from the air inlet chamber through said neck, a self-regulating air pressure valve interposed in said air duct, an air inlet tube protecting the receiving end of the air duct, and a dome-shaped cap extending over said tube.

3. An automatic regulator for gasoline 120

burners, comprising a hollow body having an air inlet chamber, and an air passage leading from the chamber, an interiorly positioned air nozzle spaced from the wall of the body to form a gasoline chamber, said nozzle communicating with said air passage; an adjustable air valve controlling said passage between the air inlet chamber and nozzle, a neck provided with a gasoline supply passage leading to said gasoline chamber, an adjustable needle valve controlling the flow of gasoline from said passage to the said gasoline chamber, an air duct leading from the air inlet chamber through said neck, and a self-regulating air pressure valve interposed in said air duct.

4. An automatic regulator for gasoline burners, comprising a hollow body having an air inlet chamber and an air passage leading from the chamber, an interiorly po-

sitioned air nozzle spaced from the wall of the body to form a gasoline chamber, said nozzle communicating with said air passage; an adjustable air valve controlling said passage between the air inlet chamber and nozzle, a neck provided with a gasoline supply passage leading to said gasoline chamber, an adjustable needle valve controlling the flow of gasoline from said passage to the said gasoline chamber, an air duct leading from the air inlet chamber through said neck, and a self-regulating air pressure valve interposed in said air duct.

In testimony whereof I affix my signature in presence of two witnesses.

FRANCIS A. JOHNSON.
